UNITED STATES PATENT OFFICE.

WHEELER H. VIBBER, OF NEW LONDON, CONNECTICUT, ASSIGNOR OF ONE-HALF TO
THE GILLETTE-VIBBER CO., OF NEW LONDON, CONNECTICUT, A CORPORATION.

TERMINAL-FITTING FOR ELECTRICAL INSTALLATIONS.

1,385,650.

Specification of Letters Patent. Patented July 26, 1921.

Application filed August 9, 1920. Serial No. 402,263.

To all whom it may concern:

Be it known that I, WHEELER H. VIBBER, a citizen of the United States, residing at New London, in the county of New London 5 and State of Connecticut, have invented a new and useful Improvement in Terminal-Fittings for Electrical Installations; and I do hereby declare the following, when taken in connection with the accompanying drawings and the characters of reference marked thereon, to be a full, clear, and exact description of the same, and which said drawings constitute part of this application, and represent, in—

15 Figure 1, a view in side elevation of a terminal fitting embodying my invention.

Fig. 2, a view thereof in end elevation.

Fig. 3, a view thereof in longitudinal section as applied to a conduit-pipe shown in 20 section and broken away.

Fig. 4, a view in transverse section on the line 4—4 of Fig. 1.

Fig. 5, a detached plan view of the mounting-nut.

25 My invention relates to an improvement in terminal fittings of the type employed to lead service wires out of a conduit-pipe to a lighting or other translating device, the object being to produce a simple, convenient 30 and effective device of the character described, constructed with particular reference to cheapness of manufacture, compactness of form and attractiveness of appearance.

35 With these ends in view my invention consists in a terminal fitting having certain details of construction as will be hereinafter described and pointed out in the claims.

In carrying out my invention as herein 40 shown, I employ an insulating head 5 made of porcelain or other equivalent insulating material and shown as having a rounded outer end formed with three radiating outlets 6 though the form of the head and 45 the number of outlets may be varied as required. At its inner end, the head is formed with a circumferential groove 7 for the reception of a retaining-flange 8 produced by turning inwardly the outer end of a mounting band 9 formed of relatively thin sheet metal and having its inner end turned in-

wardly to form a retaining-flange 10 which is, as it were, clasped over the outer face of a mounting-nut 11 the internal threads of which provide for screwing the fitting 55 upon the externally threaded end of the conduit-pipe 12, upon which the inner end of the head 5 is seated as shown in Fig. 3. As shown the said mounting-nut 11 is an ordinary standard hexagon conduit lock-nut 60 of a size just adapted to enter the mounting band 9 so that the high points of its facets will engage with the inner periphery thereof.

In case the nut and band should tend to slip one upon the other, the band being thin, 65 will deform sufficiently to permit a wrench to grip the facets of the nut through the metal of the band.

I do not, however, limit myself to the use of a hexagonal or polygonal nut, since I 70 might employ other means such as solder, for coupling the nut and band for rotation together, my invention being characterized by the utilization of a standard commercial conduit lock-nut non-rotatably mounted in 75 a light sheet-metal band carrying the insulating head in place of a metal sleeve heavy enough to be internally threaded for being screwed directly upon the conduit-pipe, and on account of being heavy enough for that 80 purpose, difficult to have its outer end crimped into the circumferential groove of the head without danger of cracking the same. These objections are avoided by my invention, by which I also secure economy 85 of space and material.

I claim:

1. A terminal fitting for electrical installation, having an insulating-head formed with a peripheral groove, a nut adapted to 90 be mounted upon the threaded end of a conduit-pipe, and a light sheet-metal mounting-band having one end turned into the said peripheral groove of the insulating-head, and its other end turned over upon the 95 said nut and adapted to be compressed thereupon for its non-rotatable connection therewith.

2. A terminal fitting for electrical installation having an insulating head formed 100 with a peripheral groove, a polygonal nut adapted to be mounted upon a conduit-pipe,

and a light sheet-metal mounting-band having one end turned into the said groove and its other end turned over upon the outer face of the said nut upon the high points of 5 which the band is compressed for its non-rotatable connection therewith.

In testimony whereof I have signed this

specification in the presence of two subscribing witnesses.

WHEELER H. VIBBER.
